[57] CLAIM

The ornamental design of a three faceted broken front face of a retaining wall block, as shown and described.

DESCRIPTION

FIG. 1 is a perspective view of a three faceted broken front face of a retaining wall block showing my new design; FIG. 2 is a top plan view thereof; FIG. 3 is a bottom plan view thereof; FIG. 4 is a front elevational view thereof; FIG. 5 is a rear elevational view thereof; FIG. 6 is a side elevational view thereof, the opposite side being a mirror image thereof; FIG. 7 is a perspective view of a second embodiment of a three faceted broken front face of a retaining wall block showing my new design; FIG. 8 is a top plan view of FIG. 7; FIG. 9 is a bottom plan view of FIG. 7; FIG. 10 is a front elevational view of FIG. 7; FIG. 11 is a rear elevational view of FIG. 7; FIG. 12 is a side elevational view of FIG. 7, the opposite side being a mirror image thereof; FIG. 13 is a perspective view of a three faceted broken front face of a retaining wall block showing my new design; FIG. 14 is a top plan view of FIG. 13; FIG. 15 is a bottom plan view of FIG. 13; FIG. 16 is front elevational view of FIG. 13; FIG. 17 is a rear elevational view of FIG. 13; and, FIG. 18 is a side elevational view of FIG. 13, the opposite side being a mirror image thereof. The broken lines in the drawings illustrate modifications of retaining wall blocks that include the broken front face of the design.
